[57] CLAIM

The ornamental design for an eyeglass hinge, as shown and described.

DESCRIPTION

FIG. 1 is a front side elevational view of an eyeglass hinge in accordance with my invention;

FIG. 2 is a top plan view of the eyeglass hinge of FIG. 1, the bottom view being the same;

FIG. 3 is a lefthand end elevational view of the eyeglass hinge of FIG. 2;

FIG. 4 is a righthand end elevational view of the eyeglass hinge of FIG. 2; and,

FIG. 5 is a rear side elevational view of the eyeglass hinge of FIG. 1.
